UNITED STATES PATENT OFFICE

97,873

DESIGN FOR CHESSMEN

Doris Stevens Thompson, Painesville, Ohio

Application May 25, 1935, Serial No. 57,025

Term of patent 3½ years

To all whom it may concern:

Be it known that I, Doris Stevens Thompson, a citizen of the United States, residing at Painesville, county of Lake, State of Ohio, have invented a new, original, and ornamental Design for Chessmen, of which the following is a specification, reference being had to the accompanying drawing, forming a part thereof.

In the drawing:

Fig. 1 is a perspective view of the chessman known as the queen.

Fig. 2 is a perspective view of the chessman known as the king.

Fig. 3 is a perspective view of the chessman known as the bishop.

Fig. 4 is a perspective view of the chessman known as the knight.

Fig. 5 is a perspective view of the chessman known as the castle.

Fig. 6 is a perspective view of the chessman known as the pawn.

I claim:

The ornamental design for chessmen substantially as shown and described.

In testimony whereof, I hereunto affix my signature.

DORIS STEVENS THOMPSON.
